UNITED STATES PATENT OFFICE.

ERASTUS C. DEAN, OF ECONOMY, PENNSYLVANIA.

CHIMNEY-CAP.

SPECIFICATION forming part of Letters Patent No. 792,202, dated June 13, 1905.

Application filed February 23, 1904. Serial No. 194,700.

To all whom it may concern:

Be it known that I, ERASTUS C. DEAN, a citizen of the United States, residing at Economy, in the county of Beaver, State of Pennsylvania, have invented certain new and useful Improvements in Chimney -Caps; and I do hereby declare the following to be a full, clear, and exact description of the invention, such as will enable others skilled in the art to which it appertains to make and use the same.

This invention relates to chimney-caps; and it has for its object to provide a construction wherein the proper draft in the chimney will be maintained irrespective of the direction or force of any prevailing wind, a further object of the invention being to provide a cap which will be simple in construction and durable.

In the drawings forming a portion of this specification, and in which like numerals of reference indicate similar parts in the several views, Figure 1 is a perspective view showing a cap embodying the present invention. Fig. 2 is a vertical section taken centrally through the cap. Fig. 3 is a perspective view showing the top of the cap in inverted position.

Referring now to the drawings, the present cap comprises a hollow base portion 5, which is adapted to fit over the top of the chimney and upon which is mounted the body portion of the cap. The body portion of the cap comprises the four side walls 6, each of which is curved in a vertical plane first outwardly from the base and then inwardly over the base and beyond the bottom opening of the latter, leaving the top opening 7, which is much smaller than the lower opening of the base. The end edges 8 of the sides 6 of the body are brought together excepting at the lower portions thereof, where are left the openings 9, these openings, as illustrated, being at the bottoms of the corners of the body.

Upon the top of the body—that is, upon the inwardly-curved upper portions of the walls 6—are mounted the posts 10, one at each corner of the opening 7, and upon these posts is mounted a top plate 11, which is held above the top opening of the body.

Upon the lower face of the top plate 11 and within the inclosure of the posts 10 is secured a convex plate 13, which projects downwardly or in the direction of the opening 7.

It is found that in practice a chimney equipped with this cap is not influenced by prevailing winds and that the draft through the chimney is efficient at all times.

What is claimed is—

A chimney-cap comprising an open base having its upper edges inclined inwardly; four side walls, each of which is curved outwardly from the inner edge of the corresponding inclined portion of the base and turned inwardly at the top, forming a contraction between the base and body, an open top, and an intermediate bulging portion of the said body, the inwardly-turned upper portions of the sides extending toward but terminating short of one another to form a top opening smaller than the opening in the base, the adjacent edges of the sides being in contact except at the said contraction between the base and body; posts secured upon the upwardly-in-turned portions of the walls, each post being mounted upon two of said walls at their adjacent meeting faces; a plate mounted upon the posts; and a convex plate attached to the lower side of the first-mentioned plate and disposed over the said top opening.

In testimony whereof I affix my signature in presence of two witnesses.

ERASTUS C. DEAN.
